Primary Examiner — Angela J Lee(74) *Attorney, Agent, or Firm* — Frommer Lawrence & Haug LLP; Ronald R Santucci**CLAIM**

The ornamental design for a monitor support device, as shown and described.

DESCRIPTION

FIG. 1 is a front perspective view of the monitor support device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a rear perspective view thereof.

The broken lines in the figures are for the purpose of illustrating environmental features including springs and screw fasteners that form no part of the claimed design.
